UNITED STATES PATENT OFFICE.

JAMES H REICHART, OF MUNCIE, INDIANA.

DESIGN FOR A COMBINED FIRELESS-COOKER CASING AND ELECTRICAL HOT-PLATE.

57,266.

Specification for Design.

Patented Mar. 8, 1921.

Application filed October 7, 1920. Serial No. 415,454. Term of patent 14 years.

To all whom it may concern:

Be it known that I, JAMES H. REICHART, a citizen of the United States, residing at Muncie, in the county of Delaware and State of Indiana, have invented a new, original, and ornamental Design for a Combined Fireless-Cooker Casing and Electrical Hot-Plate, of which the following is a specification; reference being had to the accompanying drawing, forming part thereof.

The drawing is a perspective view of a combined fireless cooker casing and electrical hot plate, showing my new design.

I claim:

The ornamental design for a combined fireless cooker casing and electrical hot plate, as shown.

JAMES H. REICHART.
